LATHE CONSTRUCTION

Clay E. McElroy, 1844 4th St. SE., Moultrie, Ga.
Filed May 27, 1960, Ser. No. 32,335

1 Claim. (Cl. 29—27)

This invention relates to a lathe construction, and has as its primary object the provision of an improved turning tool characterized by interchangeable elements whereby the same may be readily adapted to face plate turning, as in working wood or the like, or for metal spinning.

An additional object of the invention is the provision of such device characterized by a work holder which may be readily positioned so that the operator may stand in front of the face plate while doing face plate work, and may work on the rear of the face plate, without the necessity of reversing the material being worked upon.

An additional object of the invention is the provision of a small, compact machine which may be readily adapted to face plate work on articles of relatively great diameter.

Still another object of the invention is the provision of such a tool or machine characterized by the ready interchangeability of parts, and particularly by a split bearing assembly wherein the spindle assembly may be removed from the headstock, and replaced as an integral unit, without the necessity of tearing down the machine.

A further object of the invention is the provision of a device of this character wherein the work spindle may carry on the opposite end a buffering wheel in readily accessible position, so that the same machine may be used for a relatively wide variety of operations and purposes.

Still another object of the invention is the provision of a device of this character which is sturdy and durable in construction, reliable and efficient in operation, and relatively simple and inexpensive to manufacture, assemble and utilize.

Still other objects will in part be obvious, and in parts be pointed out as the description of the invention proceeds, and shown in the accompanying drawing wherein there is disclosed the preferred embodiment of this inventive concept.

In the drawing:

FIGURE 1 is a side elevational view of one form of device embodying the instant inventive concept, shown as set up for metal spinning.

FIGURE 2 is a top plan view of the construction of FIG. 1 as set up for metal spinning, certain parts being indicated in dotted lines in a different position of adjustment.

FIGURE 3 is a front elevational view of the construction as viewed from the right in FIGS. 1 and 2.

FIGURE 4 is an enlarged sectional view taken substantially along the line 4—4 of FIG. 3 as viewed in the direction indicated by the arrows.

FIGURE 5 is an enlarged sectional view taken substantially along the line 5—5 of FIG. 3 as viewed in the direction indicated by the arrows.

FIGURE 6 is an enlarged sectional view taken substantially along the line 6—6 of FIG. 2 as viewed in the direction indicated by the arrows.

FIGURE 7 is a perspective view of the device showing a different attachment in place, and adapted for use in face plate turning, and

FIGURE 8 is a view similar to FIG. 7, but showing the work holder of FIG. 7 in a different position of adjustment enabling work to be done on the rear of the article.

Similar reference characters refer to similar parts throughout the several views of the drawing.

Having reference now to the drawings in detail, there is generally indicated at 10 a base, which is preferably comprised of relatively heavy metal, and which is adapted to be positioned on and secured to a workbench or table

2

or the like. Mounted at one end of base 10 substantially centrally thereof is a headstock 11, which is hollow, and secured to the base as by means of bolts 12 extending through suitable apertures in the corners thereof. At its upper extremity, headstock 11 is provided with a relatively flat top surface 13, the ends of which are provided with semi-circular bearing receiving depressions 14, in which depressions a spindle assembly, generally indicated at 15 (see FIG. 4), is adapted to seat. The spindle assembly is comprised of a central shaft 16, which is exteriorly threaded at its opposite ends as at 17, and provided with an interior bore 18 which tapers toward the opposite ends 19 to provide for the insertion of a suitable tool in either end thereof.

Each end of the spindle assembly carries a bearing unit comprised of an inner race 20 and an outer race 21, between which are positioned ball or roller bearings 22, with the outer race 21 normally seating in the arcuate recess 14. A central V belt sheave block 25 surrounds the central portion of shaft 16, and is held in position by means of set screws 26, pulleys of various diameters being provided, a selected one of which is adapted to be encircled by a V belt 27, which extends downwardly to a suitable drive motor (not shown) which may be positioned beneath the base or beneath the table or workbench with which it is associated.

Between the inner bearing races 20, and the adjacent ends of the pulley block 25, there are positioned compressible collars 28, the purpose of which will be more fully described hereinafter.

Headstock 11 is provided with a headstock cover 30, which is provided with suitable enlargements 31 for the reception of the top of the sheave block 25, and which includes outwardly extending flanged portions 32, which, when the spindle assembly 15 is in position, are adapted to be secured to the flat top surface 13 by means of suitable bolts 33. The end portions of cover 30 are provided with complementary semi-circular recesses 34, which serve completely to encircle and securely hold the outer bearing races 21.

When the spindle assembly is in position suitable plates 35 which surround the sleeve 16 adjacent its ends are secured as by means of screws 36 to the ends of the cover and headstock, as best shown in FIG. 1.

End plates 35 surround suitable clamping or lock nuts 37, which engage the threaded ends 17 of sleeve 16, and serve to hold the bearing assemblies against the compressible gaskets 28 and against the sheave block 25 in such manner that the entire unit may be removed integrally without the necessity for disassembly, merely by releasing the screws 33, and four of the screws 36, and removing the cover 30.

As best shown in FIG. 1, a face plate 40 may be suitably positioned in the inner end 19 of sleeve 16 in a conventional manner, and provided with a projecting screw 41, for the support of a chuck or the like.

A buffering wheel 42 may be mounted on the other threaded end 17 of shaft 16 and employed simultaneously with the face plate without the necessity of any removal or reversal of parts.

The opposite end of base 10 carries adjacent one side thereof a boss 45, which is provided with a series of spaced apertures 46, adapted for the selective reception of pins 47 carried by the base 48 of an offset tail stock overarm 49. An additional series of apertures 50 extend at spaced intervals along boss 45, for the reception of a screw 51 which includes a head 52 having a universal joint handle member 53 pivoted thereto as by means of a pivot 54, so that the entire arm and its related components may be removed from the boss when not in use, or suitably secured thereto or adapted to be used in a manner and for a purpose presently to be described.

The upper end of arm 49 carries a split clamp 55, the upper and lower portions of which are provided with threaded bores, through which extends a clamping screw 56 having an operating knob 57 on the upper extremity thereof. The interior of the threaded clamp 55 is threaded for the accommodation of a screw 60, which is provided at one end with a projection arm 61 which carries an operating crank 62 opposite which is provided a counter weight 63 all in known or conventional fashion. The screw 60 carries at its other end a pressure bearing assembly 64, which serves as a tailstock when the apparatus is used for metal spinning or the like. The arm is so designed that the tailstock is accurately aligned with the headstock or chuck, so that the apparatus may be effectively used as a lathe. By suitable selection of the apertures 46 into which the pins 47 are engaged, the effective distance between the headstock and the tailstock may be readily varied so that comparatively long or comparatively short pieces of work may be employed.

When it is desired to spin metal on the device, a tool support may be employed. A spinner tool post 81 is suitably inserted in a bore in a boss 72. The upper end of post 81 is reduced as at 82, and is adapted to engage in a selected hole 83 in a spinner tool rest 84, which may thus be suitably angled to accommodate a metal working tool. An upwardly extending pin 85 also having a reduced end portion 86 may be positioned on the upper side of the tool rest 84, by insertion of one of the holes 83 from the top, as best shown in FIG. 3. In this arrangement the tool rest 84 may be obviously moved to a wide variety of positions, as indicated by dotted lines in FIG. 2.

When it is desired to use the apparatus for face plate turning the arm 49 and its associated components are removed, by the use of the operating handle 53 for releasing the screw 51 from its related aperture 50.

For face plate turning the threaded member 41 is removed, together with the face plate 40, and any suitable means employed, for mounting an article to be turned thereon, as best shown in FIGS. 7 and 8.

For use under these conditions a woodworking tool support or rest 70 of conventional design, as best shown in FIG. 7, is mounted by means of its shank 71 in a bore in a vertically positioned boss 72 which is mounted on a movable arm 73. The arm 73 carries a longitudinally extending slot 74, into which extends a bolt, which may be selectively secured in any one of a series of apertures 76 in a second boss 77 extending transversely across the adjacent end of the plate 10. A screw 78 provided with the sliding operating member 79 serves clampingly to engage the shank 71 within the bore of the boss 72, the arrangement being such that the upper surface of the support 70 may be suitably angled as desired. By virtue of the arrangement of the slot 74 and the nut 75, as well as the relative angularity of the member 70, it will be obvious that a plate or article to be worked on 80 may be worked upon from the front, as shown in FIG. 7, or from the rear, as shown in FIG. 8, merely by rearrangement of the arm 73. When the support 70 is used, as previously mentioned, the arm 49 is removed.

From the foregoing it will be seen that there is herein provided an improved tool, which is highly versatile, which lends itself to a variety of operations, and a variety of positions of adjustment, and which accomplishes all of the objects of this invention, and others, including

many advantages of great practical utility and commercial importance.

As many embodiments may be made of this inventive concept, and as many modifications may be made of the embodiments hereinbefore shown and described, it is to be understood that all matter herein is to be interpreted merely as illustrative and not in a limiting sense.

I claim:

In a lathe construction, in combination, a bore, a hollow head stock on said bore, said head stock including a flat top surface having a pair of aligned semi-cylindrical apertures therein and a cover having a pair of oppositely aligned semi-cylindrical openings therein, said openings registering to form cylindrical bores, end plates securing said cover to said head stock, a spindle assembly comprising a central hollow shaft having inwardly tapered end portions, a pulley block mounted on said shaft, bearings mounted on said shaft on opposite sides of said pulley block, resilient gaskets interposed between said bearings and said pulley block, said end plates having central openings through which the ends of said spindle assembly extend, clamping nuts including sleeve portions extending into said openings in said end plates holding said pulley block gaskets and bearings on said shaft; said spindle assembly seating removably and rotatably in said cylindrical bore, a chuck carried by one end of said spindle assembly, a boss on said base having a series of openings therein, a tail stock overarm selectively mounted in one of said openings, a universal joint handle clampingly engaging said tail stock overarm in said selected opening, a clamping jaw carried by said overarm, a horizontally positioned adjusting screw for said jaw, an operating handle for said adjusting screw, a counterweight for said operating handle, a second boss having a series of apertures therein mounted on said base adjacent said overarm, a tool rest selectively mounted in one of said apertures, said tool rest including a holder comprising an elongated boss having a slot therein, a pin extending through said slot adjustably securing said elongated boss to said second boss, a vertical spinner tool post having a reduced end mounted on one end of said elongated boss, a horizontal spinner tool rest mounted on said post having a plurality of openings therein, into one of which said reduced end extends for angular adjustment of said tool rest, an upwardly extending tool rest pin selectively mounted in another of said openings in said tool rest, and a buffering wheel mounted on the end of said hollow shaft of said spindle assembly opposite the end carrying said chuck.
